KNITTING MACHINE

Gerrit Henry Nyhuis, Hobart, Ind., assignor to
 Paramount Textile Machinery Co., Chicago,
 Ill., a corporation of Illinois

Application October 7, 1937, Serial No. 167,847

4 Claims. (Cl. 66—138)

This invention has reference to knitting machines for knitting circular knit hosiery, commonly termed "seamless," and particularly to instrumentalities for knitting such an article in the so-called "ringless" construction; that is to say, its principal object is the elimination of the objectionable bands or rings noticeable in circular knit hosiery when silk yarn is used and this yarn is fed from one bobbin or spool.

10 The disadvantages of such bands or rings are fully discussed in U. S. Letters Patent granted to Charles A. Kaufman, #1,969,307, on August 7, 1934. Notwithstanding the fact that the patent is limited to full-fashioned hosiery articles, the 15 objectionable feature above referred to is found with the same characteristics in seamless hosiery, and its elimination in the last-mentioned class of articles is just as important from the standpoint of marketability as is the case with full-fashioned hosiery.

It has been discovered that one method of eliminating these rings or bands has been to knit the body of the stocking, that is to say, the portions which are revealed while the stocking is on 25 the leg, from yarns fed from more than one, and preferably three, different spools or bobbins of yarn, the said yarn being alternated for the knitting of successive courses, so that the inherent uneven nature of pure silk may be "evened 30 out" and the objectionable rings substantially eliminated, all as disclosed more in detail in said Patent #1,969,307.

A more particular object is the attainment of a stocking characterized not only by coursewise 35 uniformity of stitches, but uniformity of stitches in adjacent courses, i. e., by the latter I refer to the elimination of the "washboard" effect, well known to those in the art.

Inasmuch as sheer silk hosiery is confined principally to women, the present invention is disclosed particularly with reference to machines 40 for knitting ladies' hosiery, although it is not intended to be limited to that particular class of goods.

45 Accordingly, in addition to the principal object mentioned above, one purpose of my invention is a simple mechanism which may be attached to a knitting machine commonly used for the knitting of ladies' seamless silk hosiery made 50 of natural silk—as, for example, the widely known Scott & Williams model "K" machine, which knits a stocking beginning at the welt and formed with a double welt turned automatically in the machine, although by referring to this particular 55 construction of a stocking, I do not intend to

limit myself thereto, but wish it to be understood that the mechanism and method detailed herein may, with slight modifications, be applied to other knitting machines and to the production of different articles of a similar type without departing from the spirit of the invention.

Another object of this invention is to provide 10 yarn controlling means of a novel character co-operating with means for feeding the yarn from the several bobbins. A further purpose of the invention is the provision of yarn feeding and controlling means which may be attached to the knitting machine with very few changes in the mechanism theretofore existing, and of a simple foolproof nature.

15 Other objects of the invention will become apparent in what follows, and will be alluded to as they arise.

In the drawings, in which inconsequential parts are omitted for clarity:

Figure 1 shows a plan view of the principal portion of the attachment, with sufficient of the knitting machine shown to indicate the relationship of the parts;

Figure 2 shows a side elevation looking from 25 the left-hand side of the machine, that is to say, with the needle circle at the right;

Figure 3 shows a front elevation of a mechanism for controlling the tension of the body 30 yarns;

Figure 4 shows a plan view of the yarn controlling mechanism of Figure 3;

Figure 5 shows a side elevation of a portion of Figure 3;

Figure 6 is a detail view of a portion of the 35 yarn controlling mechanism;

Figure 7 is a detail view of the cam and follower for operating the yarn controlling mechanism shown in Figure 3;

Figure 8 is a detail of a thrust bar and yarn 40 feeding fingers operated thereby;

Figure 9 is a detail of the cam for operating the thrust bar shown in Figure 8;

Figure 10 is a diagrammatic view of the stocking 45 constructed in accordance with the invention;

Figure 11 is a detail of the yarn tension controlling mechanism of Figure 3.

Figure 12 is a side elevation of an additional 50 yarn tension controlling mechanism for the reinforcing yarn of the high splice heel and reinforced sole;

Figure 13 is a diagrammatic representation showing the comparison in the length of the floated reinforcing yarns resulting from the use of the mechanism of Figure 12, and

Figure 14 shows diagrammatically the relative positions of a few of the "ringless" knitted courses.

Now, referring to the drawings, 1 indicates diagrammatically the needle circle of the machine, which, for purposes of this disclosure, is assumed to be of the revolving cylinder type, although with modifications, the present invention may be adapted to machines in which the needle circle is fixed and the cams and their related parts revolved.

2, 3, 4 and 5 are bevel gears customarily found on the machine for effecting rotation of the dial in unison with the needle cylinder, this dial being the one carrying the bits for the automatic turning of the double welt. A frame 10 is provided for supporting the working parts of the present mechanism, and it is provided with ears 11 arranged for pivotal relationship with the shaft 12, already a part of the machine, and upon which the dial and its operating parts are arranged to swivel so that accessibility to the knitting needles is facilitated. In this manner the mechanism of the present invention being interconnected with the gears driving the dial, and on the same frame therewith, may be tilted backward with the dial when inspection of the knitting mechanism is desired, and the other parts of the improvement are so designed that it is not necessary to readjust any parts thereof when the tilting mechanism is returned to operating position.

The yarn guide 13 is the one with which the machine is equipped and the six customary yarn feeding fingers 14 remain in their former location, except that the three fingers to the right (as the observer faces the machine) are provided with lengthened rearwardly extending portions 16 for actuation by selecting fingers to be hereinafter described. The remaining three fingers are used for carrying reinforcing yarns other than those used in knitting the body portion of the stocking, and since they form no part of the present invention, will not be discussed in greater particularity.

Pivotedly arranged on a shaft 17, supported by extensions 23 of the frame 10, are the three selector levers 18a, 18b and 18c, suitably spaced by collars 19 and held in position on the shaft 17 by arms 23. The portion 24 of the selector arms 18a, 18b and 18c which co-operate with the portions 16 of the yarn fingers 15a, 15b and 15c, is arranged for adjustment with respect to the arm proper by being pivoted at 25; and through the adjusting and lock screws 26 and 27, the portion 24 may be shifted through a small angle to change the relationship between the selector lever and the yarn finger individual thereto. At the other end of each of the selector levers are cam follower rollers 28 adjustable on slotted holes in the arms 18a, 18b and 18c, so that the proper timing of the selector levers with relation to the rotation of the needle cylinder may be obtained. A shaft 32 is arranged for rotation in bearings 33 forming part of the frame 10. Affixed to one end of said shaft is a bevel gear 34 co-operating with a pinion 35, fixed to a cross shaft 36 journaled in 10. A further pinion 37 meshed with the gear 4, transmits rotation of the gear 4 through to gears 34 and 35, so that shaft 32 rotates in unison with the main driving gears 2, 3, 4 and 5. It will be noted at this point that the pinion 35 has sufficiently fewer teeth than the gear 34, so that the shaft 32 is rotated at a speed of one-third that of the gear 2. In other words, the needles cylinder rotates three times as fast as the shaft 32.

75 Of course, if more than three bobbins of body

yarn are utilized, the speed ratio of 3:1 will change accordingly, so that for four bobbins, the ratio would be 4:1, etc.

Loosely journaled on shaft 32 is the selector cam assembly 38 consisting of a drum on the surface of which are mounted the selector cams 41a, 41b and 41c operating the levers 18a, 18b and 18c through the medium of the followers 28. The cams 41a, 41b and 41c extend approximately 180 degrees around the cam drum 38, and in the said drum is provided a groove 42 to accommodate a piece of frictional material, as for example, leather belting 43 held in position in the groove 42, and in frictional relationship therewith by a spring 44, and the affixing of the other end 45 of the friction belt at some convenient point on the frame. The opposite end of the spring 44 is likewise attached to the frame in some convenient manner.

Now referring to Figure 3, it will be noted that the cam drum 38 is provided with a bushing 46 integrally a part thereof and affording a smooth rolling relationship with the shaft 32. A collar 47 maintains the drum 38 in its longitudinal position on the shaft and against the bearing 33. Affixed to the shaft 32 is a collar 52 provided with two arms 53 (Figure 1), forming a slot therebetween. The arms 53 carry screws 54 provided with lock nuts. In sliding relationship with the screws 54, and in driven contact therewith, is an arm 55 extending axially of the shaft 32 and formed integrally with the collar 56, axially of the shaft 32 and formed integrally with the collar 56, axially slidable on the shaft 32. Another arm 57 on the collar 56 is arranged to co-operate with a lug 58 integral with the drum 38 and in a recess 59 thereof. The mechanism just described will be understood to be a clutch, so that rotary motion of the shaft 32 may be transmitted through the collar 52, arm 55, collar 56, arm 57 and lug 58, to rotate the drum 38; and the axial sliding of the collar 56 is utilized to engage and disengage the drum 38 from rotation with the shaft 32.

The engagement and disengagement of the clutch assembly just described is effected by the following mechanism: On the main drum 62 of the machine (Figures 3 and 7) are cams 63 and 63a co-operating with a follower 64 supported for substantially vertical sliding movement in the framework of the machine, and maintained in contact with the cams 63 and 63a by a spring 65 fixed at its other end to some suitable point on the frame of the machine. A gap 66 between cams 63 and 63a provides for the downward movement of the bar 64. Pivotedly mounted in an arm 67 of the bar 64 is a connecting rod 68 maintained by collars 69. On the vertical portion of the connecting rod 68 is fixed a collar 72 provided with an arm 73 extending substantially at right angles to said connecting rod and arranged at its extreme end to co-operate with a pin 74 (Figure 11), on one arm of the bell crank 75, pivoted at 76 to a support 77 fixed to the frame of the machine in some convenient manner. The other arm 78 of the bell crank is arranged to co-operate with one end of the clutch lever 82, pivoted at 83 on the frame 10. The opposite end of the clutch lever 82 is provided with a pin 85 (Figure 3) slidably co-operating with a groove 86 formed in the collar 56. A spring 84 extending between clutch lever 82 and the frame 10 normally maintains the clutch engaged. Rotation of the main drum 62 will, through the cams 63 and 63a, operate the bar 64, 75

connecting rod 68, arm 13, bell crank lever 15 and clutch lever 82, and in co-operation with spring 84, move the collar 56 axially in either direction along the shaft 32, thereby to engage or disengage the clutch lever heretofore described, and either initiate the drum 38 into rotation with shaft 32, or terminate such rotation at specific intervals of time as directed by the location of the cams 63 and 63a and the pattern chain of the machine.

Through the mechanism just described it is possible to actuate the selector levers 18a, 18b and 18c through the cam drum 38 and its associated cams 41a, 41b and 41c to, in turn, operate the yarn fingers 15a, 15b and 15c in a selective manner, and at predetermined stages in the knitting process, the selection of stages being determined by the location and size of the cams 41a, 41b and 41c, and cams 63 and 63a.

Yarn fingers 15a, 15b and 15c are provided at the ends nearest the needle cylinder with the usual eyelets through which the body yarns a, b, and c, are fed to the knitting line (see Figure 3). These yarns pass upwardly through eyelets 92 and thence through eyelets 93 (Figures 4 and 5) formed in the end of arms 94, one of which is provided for each of the yarns a, b, and c. These arms 94 are made preferably of wire so as to be light, and hence rapidly responsive in operation, for reasons which will hereinafter appear, and are fixed at the end farthest from the eyelets 93 in levers 95, pivoted on a shaft 96 fixed in the frame of the machine in some convenient manner. The opposite arm of the lever 95 is provided with a spring 97, the other end of which is attached to the frame of the machine in some convenient manner, to urge the arms 94 always in a counter-clockwise direction against which rotation they are held by the yarns a, b and c passing downward to the knitting cylinder and held under a yarn clamp of any well-known type affixed to the top of the dial. The yarns a, b and c after passing through the eyelets 93, pass through eyelets 102, between tension discs 103 of a well-known type, through eyelets 104 and thence to the three bobbins from which the yarns a, b and c are feeding. The eyelets 92, 102 and 104, and the tension discs 103 are all mounted on a suitable support 105 carried by the frame of the machine.

Referring now to Figures 3, 4 and 6, there is provided a member 106 pivoted on a screw 107 in 105, and arranged to rotate thereabout, but urged in a clockwise direction by the spring 108 fixed at its other end to the frame. Integrally with the member 106 are three arms 109 formed with their extreme ends rounded or V-shaped, to facilitate their entry between the tension discs 103 to separate them for a purpose to be described. Engaging with the member 106 is a sloped cam 112 fixed to the upper end of the connecting rod 68, so that upon downward vertical actuation of the rod 68, the member 106 and its arms 109 are rotated in a counterclockwise direction against the spring 108 to force the extreme ends of the arm 109 between the halves of the tension discs and separate them. It will be noted that downward movement of the connecting rod 68 will engage the clutch and simultaneously separate the tension discs.

During the knitting of certain parts of the stocking, it is necessary to move the yarn fingers 15a, 15b and 15c from their feeding position simultaneously, and this is effected by the mechanism shown in Figures 8 and 9. Cams 113 and

113a affixed to the main drum 62 operate a thrust bar 114 having an opposite end 115 sufficiently broad to embrace the fingers 15a, 15b and 15c, and thereby operate them into and out of yarn feeding position together.

Having thus described the mechanism, the formation of the complete stocking will now be detailed. Figure 10 indicates diagrammatically the completed stocking with the toe unlooped, and outlined for clarity as in the finished shape, although it will be understood by those skilled in the art that the stocking is substantially the same diameter throughout.

The formation of the double welt A and the single welt B is done in the usual way for a stocking of the kind under construction. The welt yarn or yarns are fed as usual through yarn fingers other than 15a, 15b or 15c. Just prior to the formation of the double welt A and the single welt B, the cam drum 62 has rotated to bring the cam 113a (Figure 9) into position to operate the thrust bar 114 to actuate yarn fingers 15a, 15b and 15c, as a group, away from the knitting position. See Figure 8. This actuation permits the extended ends 16 of the said fingers to move out of engagement with the selector levers 18a, 18b and 18c, so that even though drum 38 continues to revolve, the levers 18a, 18b and 18c are ineffective to operate the yarn fingers.

The portion C of the boot proper of the stocking is knitted of body yarn for several courses to clear below the knitting line before ringless knitting is commenced. The portion C will be knit from yarn fed from one of the fingers 15a, 15b or 15c at random, the reason for this random selection being that upon completion of the previously knitted stocking the cam drum 38 and selector cams 41a, 41b and 41c are likely to be left in a position to permit either fingers 15a, 15b or 15c to move into feeding position, but for the purposes of my invention, it is immaterial which one of these fingers happens to come into position during the knitting of portion C. While portion C is being knitted the clutch is disengaged by the rotation of the cam drum 62, bringing high portion C (Figure 7) on the drum into position to move thrust bar 64 vertically and disengage the clutch. This initial actuation of one of the body yarn fingers is effected by the cam drum 62 being rotated to a position such that the cam 113a will permit the thrust bar 114 through its spring to move downwardly and release fingers 15a, 15b or 15c for movement into knitting position. At this point one of the cams 41a, 41b or 41c is in such position that the left hand end (Figure 2) of one of the selector levers 18a, 18b or 18c individual thereto, will be in its lowermost position and will permit the yarn finger, also associated therewith, to be actuated by its spring 20 into knitting position. Inasmuch as the portion C of the stocking is not revealed when on the leg of the wearer, there is no disadvantage in not incorporating ringless knitting at that zone. Over the balance of the boot and the foot portions, referred to as D and E in Figure 10, ringless knitting proceeds in the following manner:

At the end of the region C the cam drum 62 is moved by the pattern mechanism so that through the cam 63, thrust bar 64 is released downwardly to operate the clutch lever 82, and through the spring 84 put the clutch into engagement and rotate the drum 38 and its selector cams 41a, 41b and 41c. Accordingly, these selector cams and each selector lever associated there-

with, and hence the yarn fingers 15a, 15b, and 15c individual thereto, are operated alternately so that first 15a is in the knitting position and 15b and 15c out. Then 15b is in the knitting position 5 and 15a and 15c are out. Then 15c is in the knitting position and 15a and 15b are out, but not necessarily in this particular sequence, since as originally indicated, 15b may be down first or 15a or 15c first, and so on. By this selection, yarns a, 10 b and c are introduced into the stocking alternately, to produce the ringless construction. It is important to actuate each of the yarn fingers 15a, 15b and 15c into knitting position and to withdraw them therefrom with some exactness 15 to ensure a vertical band of interlocked stitches at the rear of stocking of substantially uniform width. This object is attained by the use of two cam followers 28 individual to each cam 41a, 41b and 41c adjustable with respect to each other and 20 to the selector levers 18a, 18b and 18c to determine the rise and drop of the selector levers with relation to their cams 41a, 41b and 41c.

During the reciprocating knitting of the heel pocket it is not necessary to actuate the yarn 25 fingers alternately so that the main drum through its cam 113 will operate the thrust bar 114 to move fingers 15a, 15b and 15c out of knitting position, and the same procedure is used during the knitting of the toe pocket.

30 Now having described the actual knitting operations, the operation of the yarn tension control will be referred to. When yarn a is fed, previously knitted yarns b and c are held interlaced at the rear of the stocking and travel around the 35 needle circle with the partially completed stocking, but it is necessary to provide a yarn tensioning means to prevent the yarns not being knitted from interfering with the knitting operation and to carry them under the dial without such interference. This is effected by the arms 94 which, 40 when tension is removed from the yarn individual thereto, by its removal from the knitting cycle will move upward through tension of the spring 97, as indicated by dotted lines in Figure 5. In 45 other words, the arms 94 will move from their normal to their dotted position alternately and back again, depending upon whether their individual yarns are not being, or are being, knitted into the article and depending upon the position 50 of the cylinder in its rotation. When ringless knitting is completed, the body yarns are taken out of the knitting line through operation of their fingers 15a, 15b and 15c and gripped under the clamp on the dial, as already alluded to. However, 55 when this is done it is necessary to take the tension from these yarns, otherwise they will be pulled from the binder by the urging of the springs 97. This operation is effected by the downward movement of the thrust bar 64 from 60 cam 63 or 63a to the level of cam drum 62, causing the member 106 and its associated arms 109 to enter between the discs of the disc tensions and releasing the yarns a, b and c between the discs and the binder, whereupon the arms 94 are 65 all free to move to their upper dotted line position and the yarns a, b and c become slack and cannot pull out from the binder. This operation is reversed when it is desired to recommence knitting the ringless courses.

70 Figure 14 indicates in a diagrammatic way the relationship of the "ringless" courses. The three yarns preferably employed are overlapped at the rear of the stocking, due to the introduction and withdrawal of each of the body yarns, in interlocked stitches and in a zone several wales wide.

These interlocked stitches are preferably gathered together by mock seaming the rear of the stocking in the well-known way, so that the finished article is not ordinarily distinguishable from a mock-seamed seamless stocking of the ordinary 5 type. The position and extent of the interlocked stitches are shown in Figure 10.

On a knitting machine of the type to which the device of the present invention is attached, there is ordinarily provided a pin on the underside of the dial around which the reinforcing yarns used in the high splice heel and cradle sole are partially wrapped as the needle cylinder revolves. The purpose of this pin is to provide tension on the float yarns incorporated into the 15 reinforced knitting, and to facilitate the introduction of the reinforcing yarns at the proper zones in the stocking. These float yarns are later trimmed off by hand.

In order to permit the yarns a, b and c to float 20 under the dial during ringless knitting, the dial pin must be removed, otherwise there would be interference with the float. However, when this is done, some provision must be made to substitute 25 for the actions of the dial pin and retain the tension required during knitting of the reinforcing yarns in the high splice heel and sole. The means employed are disclosed in Figure 12 where-in the reinforcing yarn is referred to as r. Yarn r after leaving the bobbin, passes through an 30 eyelet 123 affixed to the machine, eyelet 124 formed in the end of the arm 125, and eyelet 126 also affixed to the frame of the machine, and comes to the knitting position or the yarn clamp, depending whether the reinforcing yarn is being 35 knitted or held. Ordinary disc tensions 127 are also provided, but for this particular improvement have no significance. The arm 125 is affixed to a lever 128 pivoted at 129 to the machine frame. The downwardly extending arm has connected therewith a spring 132 with its opposite end affixed to the machine in any convenient manner. Another arm of the lever 128 is provided with a pin 133 coating with the bent end 134 of a rod 135 vertically slidable in a bracket 136 fastened to the frame. The lower end of the rod 135 is journaled at 137 to a thrust bar 138, the upper end of which is pivoted at 139 to a link 140 swivelling on 142 to enable the bar 138 to be moved substantially in a vertical direction. A guide or bracket 143 is provided for the lower end of the bar 138 and a spring 144 extending between the bar 138 and bracket 143 urges the bar in a downward direction against the cams 145 and 145a. It will be obvious that the upper end 40 of the bar 138 instead of being pivoted as indicated at 139 and 142, may be arranged to slide in a bracket of any convenient structure. The cams 145 and 145a are affixed to the main 45 drum 62.

50 Operation of the mechanism just described is as follows: At the proper time in the rotation of the main drum the low point between the cams 145 and 145a referred to on the drawing by the term "high splice" comes underneath the lower 55 end of the bar 138 and spring 144 moves the said bar and its connecting rod 135 downwardly. This will, in turn, permit pin 133 and its associated arm 125 to move counter-clockwise and provide tension in the yarn r. Arm 125 continues 60 released all during the knitting of the high splice so that yarn r as it is incorporated in the stocking by actuation of its particular yarn finger is constantly provided with tension, thereby substituting 65 for the tension formerly provided by the pin 70 75

under the dial. In other words, as the stocking rotates with the needle cylinder during knitting, the arm 125 will move freely upward and downward as the yarn floats under the dial in a method which will be apparent to those skilled in the art. A stop 152 affixed to the frame of the machine limits the upward movement of the arm 125 so that the spring 132 cannot move it beyond the range required for proper operation.

10 The mechanism of Figure 12 operates identically during the knitting of the double sole but by that time the main drum has revolved through the interval required for the knitting of the heel pocket, and then the low part between cams 145 and 145a, entitled on the drawing "double sole," will operate the bar 138 and its associated mechanism in the manner aforesaid.

15 The most important advantage introduced by the mechanism of Figure 12 is a shortening of 20 the floating yarn in the high splice heel and reinforced sole, formerly produced by the presence of the dial pin, since it will be seen (Figure 13) that whereas formerly the floating yarn was required to pass around the pin in the center of the 25 dial, it now floats only from one margin of the splicing to the other, shortening the length of the waste yarn considerably and resulting in substantial economies in the knitting process. This 30 difference in the lengths of the floating yarns before and after the use of my present invention is indicated diagrammatically in Figure 13. The straight full line extending between the margins of the reinforced sole or high splice, as the case 35 may be, indicates the floating yarn when using the tension device of Figure 12. The dotted line between the same margins indicates the length of the floated yarn when the dial pin is used.

I claim:

1. A knitting machine for producing seamless, 40 ringless stockings comprising a main pattern drum, a cylinder supporting a series of needles; a drive shaft with interposed gear connections for rotating said cylinder; a plurality of independently movable feeds for feeding as many 45 individual main yarns of the same kind and nominal gauge; a cam drum having circumferentially spaced cam segments for controlling interchange of said feeds in a predetermined repeating sequence, a second series of gear connections 50 from the drive shaft adapted to rotate said cam drum; and clutch means between said second series of gear connections and said drum and under the control of the main pattern drum for imparting intermittent rotation to said cam drum 55 to operate said feeds in a predetermined sequence.

2. In a knitting machine for producing seamless, ringless stockings a main pattern drum, a

rotating cylinder supporting a series of needles; a plurality of independently movable feeds for feeding as many individual main yarns of the same kind and nominal gauge; a rotatable drum normally at rest and having circumferentially spaced cam segments, one individual to each feed; means interconnecting said drum and said feeds, a driving source; a clutch interposed between said driving source and said drums; and means under the control of the main pattern 10 drum to engage and disengage said clutch and thereby initiate and terminate rotation of said drum relative to said cylinder during the knitting of predetermined portions of the stocking at a rate of speed inversely proportional to the number of feeds to actuate said feeds, so that one thereof serves its yarn for one course of the knitting, another thereof for the next course, and so on alternately and repeatedly during the 15 knitting of said predetermined portions of the 20 stocking.

3. In a knitting machine a main pattern drum, a cylinder supporting a series of needles; a plurality of independently movable feeds for feeding as many individual yarns; a rotatable drum normally at rest and having circumferentially spaced cam segments, one individual to each feed; levers interconnecting said feeds with said segments; means under the control of the main pattern 25 drum to initiate and terminate rotation of said 30 rotatable drum to operate said feeds alternately during predetermined phases of the knitting to introduce said yarns alternately into the knitted stocking; and a pair of followers on each of said levers, said followers being independently adjustable circumferentially of the drum to determine within accurate limits the points at 35 which said yarns are introduced to, and withdrawn from the knitted fabric.

4. A knitting machine for producing seamless, 40 ringless stockings comprising: a main pattern drum; a cylinder supporting a series of needles; a drive shaft with interposed connections for rotating said cylinder; a plurality of independently movable feeds for feeding any number of individual main yarns of the same kind and nominal 45 gauge; a cam drum having circumferentially spaced segments for controlling interchange of said feeds in a predetermined repeating sequence, a second series of connections from the drive 50 shaft adapted to rotate said cam drum; and means between said second series of connections and said cam drum, and under the control of said main pattern drum, for imparting intermittent rotation to said cam drum to operate said feeds 55 in a predetermined sequence.

GERRIT HENRY NYHUIS.
